beth, N. J., a corporation of New Jersey

Application May 15, 1937, Serial No. 142,734
In Great Britain June 11, 1936

10 Claims. (Cl. 112—2)

This invention relates to a type of sewing machine used in textile and analogous industries for trimming and stitching together the ends of long lengths of fabric pieces with provision for positive feed by moving the machine.

The present invention has for an object to provide a piece-end sewing machine whereby a straight joining seam may be produced, particularly in light weight fabric, without subjecting 10 it to any strain and without distorting the marginal end portions being joined.

With the above and other objects in view, as will hereinafter appear, the invention comprises the devices, combinations and arrangements of 15 parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a side elevation of a piece-end stitching machine embodying the invention inclusive of the railway upon which travels the carriage supporting the 20 sewing machine. Fig. 2 is an enlarged side elevation of the carriage with the sewing machine, viewed from the opposite side from that represented in Fig. 1. Fig. 3 is a top plan view of the machine. For the sake of clearness, the blower and its tube have been omitted. Fig. 4 is an enlarged detail view of the ratchet and pawl device for retaining the feeding chain stationary. Fig. 5 is a sectional elevation and Fig. 6 is an end elevation of the planetary gear drive for feeding the 25 carriage with the sewing machine. Fig. 7 is a detail sectional view through lines 7—7 of Fig. 3 of the device for maintaining the feeding chain taut. Fig. 8 is a detail view of the feeding mechanism.

40 In the preferred embodiment of the invention, as illustrated, 1 are upright leg-members of channel cross section supporting the cross members 2 secured to the former in any well-known manner. Secured upon the cross members are two parallel 45 spaced horizontal rails 3 of L-section connected by spacing members 4.

Adapted to freely run forward and backward along the rails 3 is the sewing machine carriage 5, the grooved wheels 6 of which rest upon the 50 rails. The carriage 5 has mounted thereon a sewing machine A, preferably of the well-known Singer class 81—24 single-thread overedge stitching type more fully illustrated in the U. S. Patent to I. F. Webb, No. 1,983,258 of Dec. 4, 1934. This 55 machine is provided with the usual cloth plate 7

and a main-shaft 8 upon which are mounted the tight belt-pulley 9 and loose belt-pulley 10.

An electric motor M, for driving the sewing machine, is also mounted on the carriage 5 and has its driving pulley 11 connected with the pulleys 9 and 10 of the sewing machine by means of the belt 12.

The present machine is also equipped with the manually operable pivotally mounted belt-shipper 13 fulcrumed on the screw 13' (Fig. 2) and 10 carrying at its rearward end the spaced upstanding belt-guiding pins 14 and bent upwardly at its forward end to constitute a handle 15. Screwed to and depending from the belt-shipper lever 13 is a bracket 16 carrying a vertically slidable and 15 downwardly spring pressed plunger 17 the lower end of which is beveled as shown in Fig. 2. A spring 18 connecting the bracket 16 with the carriage 5 urges the belt-shipper 13 in a direction to shift the belt 12 onto the loose pulley 10 to 20 stop the operation of the sewing machine.

The feeding mechanism of the sewing machine, Fig. 8, is of known construction and includes the feed-dog 79 secured upon the free end of the feed-bar 80 pivotally mounted at 81 on the feed-rocker 82. The feed-bar is connected by the short pitman 83 with the feed-lift eccentric 84 on the sewing machine main shaft 8. The feed-advance eccentric 85 is connected by the pitman 86 with the bell-crank lever 87, 88, fulcrumed at 89 on 25 the machine frame. The arm 88 of the bell-crank lever is provided with a curved and undercut slot or guideway 90 for a slide-block 91 connected to the lower end of a link 92, the upper end of which is connected at 93 to an arm 94 of 30 35 the feed-rocker 82.

The machine is further provided with a manually operable device enabling the operator to conveniently shorten the initial or finishing stitches of a seam made by the machine. This 40 device, shown in Fig. 8, differs slightly from that disclosed in the aforesaid Webb patent.

Unlike the device of said Webb patent, the slide-block 91 is connected by the short link 95 with the lower end of a manually operable bell-crank lever 96 pivotally mounted upon the screw-stud 97 entering the upstanding fixed arm 98 having its lower bent end secured to the sewing machine frame by a screw 99. The bell-crank lever 96 is provided with an arm 100 terminating 50 in a button 101 for convenient actuation by the operator. A spring 102 normally maintains the bell-crank lever 96 upwardly against the adjustable screw stop 103 threaded into the upper end 55 of the fixed arm 98, and a pin 104 on the lever

contacting the stop screw 103 in which position of the bell-crank lever 96, 100 the sewing machine will produce a seam of normal stitch length. An adjustable stop 105, secured upon the fixed arm 98 by the screw 106, limits the downward movement of the bell-crank lever 96, 100. When short stitches are desired, preferably at the beginning or ending of a seam, the operator depresses the lever 96, 100 which will shift the slide-block 91 in the arm 88 of the feed-actuating bell crank lever 87 thereby reducing the effective travel of the sewing machine feed-dog 79, as fully set forth in the Webb patent before referred to.

In Fig. 3 the belt-shipper 13 is shown in full line or "off" position and when manually shifted to dotted line or "running" position, to start the sewing machine, it is retained in that position by a shoulder on a latch-lever 19 pivoted at 20 on an ear 21 of the carriage 5. The tail of the latch-lever is relatively heavy and tends to drop under the influence of gravity and raise the front of the lever to locking position when the belt-shipper lever 13 is manually shifted to "running" position to start the sewing machine. As in the device of the Webb patent, there is preferably clamped upon one of the rails 3, near the end from which the sewing starts, a slotted block 22 from which rises a stop-pin 23 in the path of traveling movement of the spring pressed plunger 17 carried by the belt-shipper lever 13. The purpose of this stop is to assist the operator in positioning the carriage 5 with the sewing machine A in starting position preparatory to a sewing operation.

There is also preferably secured to the same rail 3 which supports the stop 22 a second slotted block 24 carrying a stop-pin 25 and a tripper 26 the rounded upper end 27 of which is in the path of traveling movement of the tail of the latch lever 19 and lifts it at the end of a sewing operation to release the belt-shipper 13 which shifts the motor belt 12 from the tight pulley 9 to the loose pulley 10 thereby stopping the sewing machine. The stop-pin 25 engages the spring pressed plunger 17 and prevents overrunning or coasting of the carriage 5 beyond seam-finishing position. The stop-blocks 22 and 24 are adjustable longitudinally of their supporting rail 3 to suit the width of the particular fabric ends 50 to be stitched together.

Secured to and rising from the carriage 5 are a pair of spaced standards 28 to the upper ends of which is fixed a bracket 29. A blower 30, bolted to the bracket, is provided with a tube 31 which terminates over an inclined chute 32 the upper end of which is disposed below the work support 7 adjacent the trimmer mechanism. The blower is driven from the motor by means of the belt 33. The function of the blower is to maintain the chute clear of trimmings severed from the piece-ends being joined and prevent such trimmings from clogging the stitch-forming and feeding mechanisms of the sewing machine.

Disposed longitudinally of and between the rails 3 is a normally stationary endless chain 34 constituting an element of an auxiliary feeding mechanism. At one end of the rails the chain embraces a sprocket-wheel 35 fixed upon a cross-shaft 36 journalled in depending brackets 37 secured to the rails 3. The cross-shaft is provided with a crank-wheel 38 disposed exterior of the rails. Also secured upon the cross shaft 36, intermediate the rails, Fig. 4 is a ratchet-wheel 39 engageable by a pawl 40 pivotally mounted at 41 upon the rail 3. The ratchet wheel and pawl

maintain the chain normally stationary. Pivotally mounted upon one of the brackets 37 at 42 is a pawl unlatching lever 43 whose upper arm 44 is adapted to lift the pawl 40 clear of the ratchet wheel 39 in order to permit endwise movement of the chain 34 by rotation of the crank wheel 38.

At the other end of the railway the chain 34 embraces another sprocket-wheel 45 journalled upon a cross-shaft 46 journalled in spaced up-standing arms 47 pivoted at 48 to laterally extending arms 49 secured in any well-known manner to the cross-member 2. The chain 34 is maintained taut by means of the adjusting rod 50 one end of which bears against the cross member 2 while its threaded free end is fitted within an internally threaded aperture in the bearing 46' for the cross-shaft 46.

Secured upon the tight belt-pulley 9 on the sewing machine main-shaft 8 is a small sprocket-wheel 51 embraced by a chain 52 which is in driving engagement with a larger sprocket-wheel 53 secured upon a housing 54 of a planetary gearing. The housing is journalled by spaced ball-bearings 55 upon a stationary bearing-bushing 56 clamped by screws 57 in the split upright standard 58 rising from the carriage 5. The housing end of the bearing-bushing is formed as a pinion 59 which meshes with a second pinion 60 fixed by means of a key 61 upon the hub of a third pinion 62 which is journalled upon a headed bearing-stud 63 entering a threaded aperture in the housing 54. Pinions 60 and 62 differ slightly in their pitch diameters and number of teeth. Pinion 62 is in driving relation with a fourth pinion 64 formed upon the end of a shaft 65 journalled in the bearing-bushing 56. A counter weight 66 is secured inside of the housing which latter is closed by the cover 67.

Secured upon the exposed end of the shaft 65 is a pinion 68 which meshes with a gear 69 secured upon the stud-shaft 69' journalled in the standard 58. Shaft 69' is retained in its bearing by the collar 70 secured to the shaft. Frictionally held upon the hub of the gear 69 is a sprocket-wheel 71 whose teeth are in permanent mesh with the upper flight of the normally stationary chain or feeding element 34 disposed between the rails 3. The mechanism just described as mounted in the housing 54 constitutes a train of forward feeding elements of which the sprocket-wheel 71 remains permanently in intermeshing relation with the chain 34. An idler sprocket-wheel 72 is journalled upon a screw stud 73 fixed in the arm 74 extending from the carriage 5 and maintains the chain 34 in mesh with the sprocket-wheel 71.

The ratio of the gear drive between the sprocket-wheels 53 and 71 is such that a relatively rapid rotation of the sprocket-wheel 53 will result in only a partial rotation of the sprocket-wheel 71, which, due to its meshing with the normally stationary chain or feeding element 34, will cause the carriage 5, with the sewing machine, to move or be propelled along the rails 3 at a stitching speed substantially commensurate with that of the regular feeding movements of the feed-dog. Should there occur a difference between the travel of the carriage 5 and the work-advancing movements of the feed-dog of the sewing machine, this is compensated for by slippage of the sprocket-wheel 71 which is frictionally retained upon the hub of the gear 69 by the spring-washer 75 retained upon the shaft 69 by nuts 76.

In the operation of stitching two piece-ends 75

together, these are secured upon the impaling pins 17 in overlapping relation, with their free ends disposed beneath the presser-foot 18 of the sewing machine. The electric motor is then 5 started by a conventional toggle-switch S mounted upon the carriage 5 and, as the driving belt 12 from the motor M to the sewing machine A is on the loose pulley 10, the carriage 5 with the sewing machine will remain stationary. When it is desired to begin stitching, the belt is shifted from 10 the loose pulley 10 to the tight pulley 9 by manual manipulation of the shipper 13 which is retained in "running" position by the latch-lever 19. The shift of the belt-shipper 13 carries the 15 spring pressed plunger 17 to one side of the stop-pin 23 and frees the carriage 5 from the stop-pin.

When the motor belt 12 is shifted from the loose to the tight pulley on the sewing machine 20 main-shaft 8, stitching will begin and, by means of the sprocket-chain drive 52 between the sprocket-wheels 51 and 53, the planetary speed-reducing gearing will be set in motion and, through the sprocket-wheel 71 meshing with the 25 normally stationary chain or feeding element 34, the carriage 5, with the sewing machine A, will be propelled along the tracks 3.

As the carriage 5 with the sewing machine approaches the end of its range of travel, the 30 latch-lever 19 will be released by engagement with the rounded upper end 27 of the tripper 26 and, through the action of the spring 18, the belt-shipper 13 will be moved to "off" position, shifting the belt 12 from the tight pulley 9 to the 35 loose pulley 10, which will permit the sewing machine to come to rest.

When the carriage 5, with the sewing machine, has arrived at the end of its range of travel in completion of a piece-end stitching operation, the 40 carriage is manually returned to starting position at the other end of the rails by giving the chain 34 a partial circulatory movement, effected by manually turning the crank-wheel 38, after preliminary manual release of the pawl 40 from the ratchet-wheel 39. The chain 34, being still in 45 mesh with the now nonrotary sprocket-wheel 71, will return the carriage to initial position.

As the carriage 5 with the sewing machine approaches its starting position the inclined end of the spring-pressed plunger pin 17 will ride over 50 the top of the stop-pin 23 all as fully described in the Webb patent before referred to.

It will be observed that the feeding element constituted by the chain 34 is stationary while the 55 carriage 5, with the sewing machine A, is being propelled in one direction along the tracks 3 during a piece-end stitching operation but that the feeding element or chain 34 is circulatorily movable when the carriage 5 is manually returned 60 to starting position.

The invention is not to be understood as limited to the specific embodiment thereof chosen for the purposes of the present disclosure.

Having thus set forth the nature of the invention what we claim herein is:

1. In a machine of the class described, the combination with a railway and a wheeled carriage mounted thereon, of a sewing machine mounted on said carriage and including stitch-forming and work-feeding mechanisms, an electric motor mounted on said carriage for driving said sewing machine, a normally stationary chain disposed lengthwise of said railway, a connection including a speed reducing gearing between said 75 chain and said carriage for moving the latter with

said sewing machine on said railway at stitching speed and means including said chain for returning said carriage with said sewing machine to starting position on said railway.

2. In a machine of the class described, the 5 combination with a railway and a wheeled carriage mounted thereon, of a sewing machine mounted on said carriage and including stitch-forming and work-feeding mechanisms, an electric motor mounted on said carriage for driving 10 said sewing machine, a normally stationary chain disposed lengthwise of said railway, a connection between said chain and said carriage for moving the latter with said sewing machine on said railway, and means including said chain for returning 15 said carriage with said sewing machine to starting position on said railway.

3. In a machine of the class described, the 20 combination with a railway and a wheeled carriage mounted on said carriage and including stitch-forming and work-feeding mechanisms, an electric motor mounted on said carriage for driving 25 said sewing machine, a normally stationary chain disposed lengthwise of said railway, a connection between said chain and said carriage for moving the latter with said sewing machine on said railway, and manually operable means including said chain for returning said carriage with said sewing machine to starting position on said railway. 30

4. In a machine of the class described, the 35 combination with a railway and a wheeled carriage mounted thereon, of a sewing machine mounted on said carriage and including stitch-forming and work-feeding mechanisms, an electric motor mounted on said carriage for driving 40 said sewing machine, a chain disposed lengthwise of said railway, means for maintaining said chain stationary, a connection between said chain and said carriage for moving the latter with 45 said sewing machine on said railway, and manually operable means, including said chain, for returning said carriage with said sewing machine to starting position on said railway.

5. In a machine of the class described, the 50 combination with a railway and a wheeled carriage movable thereon, of a sewing machine mounted upon said carriage and including stitch-forming and feeding mechanisms, an electric motor mounted upon said carriage, a driving connection between said motor and said sewing machine, a chain disposed lengthwise of said railway, a driving connection between said motor and said chain independent of said sewing machine feeding mechanism for moving said carriage 55 on said railway and means including said chain for returning said carriage with said sewing machine to starting position on said railway.

6. In a machine of the class described, the 60 combination with a railway and a wheeled carriage mounted thereon, of a sewing machine mounted upon said carriage and including stitch-forming, work-feeding and trimming mechanisms, an electric motor mounted on said carriage, a driving connection between said motor 65 and said sewing machine, a blower mounted upon said carriage, a driving connection between said motor and said blower, a trimmer chute and a tube for directing a blast of air from said blower into said chute to clear the latter of trimmings. 70

7. In a machine of the class described, the 75 combination with a railway and a carriage mounted thereon, of a sewing machine and driving motor therefor both mounted on said carriage, permanently intermeshing elements

mounted respectively on said carriage and railway, driving means between said motor and the carriage-supported element for propelling the carriage in one direction, and actuating means connected with the railway-supported element for propelling the carriage in the opposite direction.

8. In a machine of the class described, the combination with a railway and a carriage mounted thereon, of a sewing machine and a driving motor therefor mounted on said carriage, permanently intermeshing elements mounted respectively on said carriage and railway, driving means between said motor and the carriage-supported element for propelling the carriage in one direction, means for interrupting the propulsion of the carriage in said direction, and actuating means connected with the railway-supported element and adapted to operate while said driving means is inactive for propelling the carriage in the opposite direction.

9. In a machine of the class described, the combination with a railway and a carriage mounted thereon, of a sewing machine and a driving motor therefor both mounted on said

carriage, a train of carriage-feeding elements mounted on said carriage, a normally stationary feeding element in permanent mesh with one of the elements of said train and mounted on and extending lengthwise of said railway, a driving connection between said train of elements and said motor, and actuating means applied to said normally stationary feeding element, for propulsion of the carriage while the elements of said train are inactive.

10. In a machine of the class described, the combination with a railway and a carriage mounted thereon, of a sewing machine and a driving motor therefor both mounted on said carriage, a train of forward-feeding elements including a sprocket wheel mounted on said carriage, a driving connection between said motor and said forward-feeding train, a normally stationary sprocket chain mounted upon said railway in permanent mesh with said sprocket wheel, and means for propelling said sprocket chain endwise for back feeding the carriage.

HERBERT CORRALL.
JAMES HEGGIE.
